UNITED STATES PATENT OFFICE

2,644,435

AIR COOLING FOR INTERNAL-COMBUSTION ENGINES

Ralph A. Hoxie, Detroit, Mich., assignor to Continental Motors Corporation, Detroit, Mich., a corporation of Virginia

Application June 24, 1947, Serial No. 756,578

5 Claims. (Cl. 123—41.65)

1

This invention relates to air-cooled internal combustion engines, particularly to such engines of the V-type.

In engines of the type specified, distribution of the cooling air mass should be such as to assure uniform cooling for most effective and efficient engine operation. Bad distribution of the cooling air will result in undercooling some portions and overcooling others.

It is an object of this invention to provide an air-cooled internal combustion engine in which the cooling air is distributed for maximum and uniform cooling. This is accomplished by the use of a fan and baffles arranged to distribute cooling air over those portions of the engine which would otherwise not be properly cooled.

In the drawings:

Fig. 1 is a section through a portion of the engine substantially at right angles to the crank-shaft, and

Fig. 2 is a view in section substantially on line 2—2 of Fig. 1.

Fig. 3 is a perspective view of the inter-cylinder baffle.

This invention is embodied in an air cooled internal combustion engine of the V-type. Inasmuch as the two banks of the V are substantially the same for the purposes of this invention, only one bank of cylinders is shown in Fig. 1, and it will be understood that the engine is substantially symmetrical about center line X—X.

According to the invention, a plurality of cylinders 2 provided with cooling fins 4 is arranged in the form of a V, one bank or leg of which is shown in the drawings. In addition to the numerous fins 4 which form planes substantially perpendicular to the cylinder axis, each cylinder is also formed with numerous pompadour fins 6 which form planes substantially parallel to the cylinder axis.

The space between the two banks of the V is covered by a closure indicated generally at 8. An air passage 10 is provided through the closure. The passage 10 is preferably annular to receive a ring of vanes 12 rotatably mounted on a fan or blower wheel 14. The fan is driven by the crankshaft in a manner which is disclosed in detail and claimed in patent application Serial Number 747,025, filed May 9, 1947, now abandoned, and assigned to the assignee of this invention. A portion 16 of the closure may be hinged to provide access to certain portions of the cylinders, for the replacement of spark plugs, etc.

The engine shown is an overhead valve type

10 having an overhead camshaft 18. A plurality of inter-cylinder connectors 20 form a continuous housing or casing for the camshaft.

In order to give the desired direction to cooling air flowing over the fins, the cylinders are provided with baffles in the vicinity of the pompadour fins. The baffles are mounted on the cylinder heads by means of mounting ears 22. Each baffle is provided with a projection 24 which partially overlies the pompadour fins at 26. As can be readily seen in Fig. 2, the projections 24 of adjoining baffles of adjacent cylinders substantially meet or come together at 28 to prevent air flow past the baffles in an axial direction.

15 The projections 24 are secured to the mounting ears 22 by ribs 30. The ribs 30 of two adjoining baffles come together to form a V as can be seen in Fig. 2. Air flows between two branches of the V and on to the pompadour fins.

20 Opposite the rib 30, each baffle is provided with another projection 32. The two projections 32 meet as can be seen in Fig. 2; this meeting of the projections, plus the fact that the projections 32 substantially abut against the underside of the inter-cylinder connector 20, serves to prevent any appreciable flow of air completely past the baffles in a direction perpendicular to the plane of the cylinders.

Operation

25 In operation, the fan 14 rotates in such a way as to blow air upward, thus inducing air to flow inward and upward from the sides of the engine outside the V. Air is forced to flow over the pompadour fins 6 by the baffles. The path of the air flow is as follows: between the two projections 30 as shown by the arrows 34; in the direction of the crankshaft axis as shown by arrows 36; downward and over the pompadour fins 6, as shown by arrows 38; in the direction of the crankshaft axis toward the space between cylinder heads as shown by arrows 40; and transversely of the cylinders toward the fan as shown by arrows 42.

30 Without the baffles, it is clear that the mass of cooling air would follow the line of least resistance which would in that case be such as to bypass the pompadour fins 6. The fins 6 would thus be inadequately cooled, resulting in hot spots on the cylinder heads and consequent inefficient operation of the engine.

I claim:

35 1. In an air-cooled internal combustion engine comprising a plurality of aligned cylinders forming a bank of cylinders, a crankshaft common to

all such cylinders, cooling fins on the cylinders disposed normal to the cylinder axes and pompadour fins on each cylinder head lying in planes extending generally parallel to the crankshaft and cylinder axes, a blower supported in juxtaposition to said cylinders and constructed to induce air flow generally normal to the engine plane containing said cylinder and crankshaft axes, and baffle assemblies mounted on the cylinder and comprising a floor portion having projections which partially overlie said pompadour fins and which bridge the gap between the pompadour fins of adjacent cylinders, said baffle assemblies further each provided with a rear wall blocking direct flow of some of the air through the gap between said cylinders and deflect same laterally into direct heat conducting relation with said pompadour fins.

2. In an air-cooled internal combustion engine comprising a plurality of aligned cylinders forming a bank of cylinders, a crankshaft common to all such cylinders, cooling fins on the cylinders disposed normal to the cylinder axes and pompadour fins on each cylinder head lying in planes extending generally parallel to the crankshaft and cylinder axes, a blower supported in juxtaposition to said cylinders and constructed to induce air flow generally normal to the engine plane containing said cylinder and crankshaft axes, and baffle assemblies mounted on the cylinder and comprising a floor portion having projections which partially overlie said pompadour fins and which bridge the gap between the pompadour fins of adjacent cylinders, said baffle assemblies further each provided with a rear wall blocking direct flow of some of the air through the gap between said cylinders and deflect same laterally into direct heat conducting relation with said pompadour fins, said laterally deflected air being turned back by the cylinder and caused to flow generally parallel with said pompadour fins and thence discharge through the gap between said cylinders below the floor portion of said baffle assembly.

3. In an air-cooled internal combustion engine comprising a plurality of aligned cylinders forming a bank of cylinders, a crankshaft common to all such cylinders, cooling fins on the cylinders disposed normal to the cylinder axes and pompadour fins on each cylinder head lying in planes extending generally parallel to the crankshaft and cylinder axes, a blower supported in juxtaposition to said cylinders and constructed to induce air flow generally normal to the engine plane containing said cylinder and crankshaft axes, and baffle assemblies mounted on the cylinder and comprising a floor portion having projections which partially overlie said pompadour fins and which bridge the gap between the pompadour fins of adjacent cylinders, said baffle assemblies further each provided with a rear wall blocking direct flow of some of the air through the gap between said cylinders and deflect same laterally into direct heat conducting relation with said pompadour fins, said laterally deflected air being turned back by the cylinder and caused to flow generally parallel with said pompadour fins and

thence discharge through the gap between said cylinders below the floor portion of said baffle assembly, said baffle assembly comprising complementary sections secured respectively to adjacent cylinders and symmetrically disposed in abutted position along a plane extending normal to the crankshaft and midway between the two adjacent cylinder axes.

4. In an air cooled V-type internal combustion engine having a crankshaft and a plurality of cylinders arranged into two banks of aligned cylinders, a closure for the space between the cylinder banks, an air passage through the closure, a blower in the air passage and operable to induce air flow between the cylinders, cooling fins on the cylinder heads and extended in a plane parallel to the crankshaft and normal to the air flow between said cylinders, a baffle on each cylinder head, and a projection on the baffle overlying at least a portion of the cylinder head cooling fins, said baffle comprising a baffle portion deflecting said air flow laterally and downwardly into contact with said cylinder head fins, said baffle comprising complementary sections respectively secured to adjacent engine cylinders and disposed in abutting relation and symmetrically arranged with respect to an engine plane extending normal to the engine crankshaft and midway between the two adjacent cylinders to which said sections are secured.

5. In an air-cooled V-type internal combustion engine having a crankshaft and a plurality of cylinders arranged into two banks of aligned cylinders, a closure for the space between the cylinder banks, an air passage through the closure, a blower in the air passage and operable to induce air flow between the cylinders generally normal to the engine plane containing the cylinder and crankshaft axes, cooling fins on the cylinder heads and extended in a plane parallel to the crankshaft and normal to the air flow between said cylinder, a baffle on each cylinder head, and a projection on the baffle overlying at least a portion of the cylinder head cooling fins, said baffle comprising a baffle portion deflecting said air flow laterally and downwardly into contact with said cylinder head fins.
